DOUGHNUT MACHINE

Peter J. Toews, Minneapolis, Minn.

Application December 5, 1936, Serial No. 114,395

20 Claims. (Cl. 53—7)

My invention relates to doughnut machines and particularly to the type of doughnut machine in which the doughnuts are progressed along a way through the flow of the cooking liquid and successively delivered to a turnover device and a discharge device.

An object of the invention resides in a construction by means of which the rate of travel of the doughnuts through the machine may be positively controlled.

Another object of the invention resides in providing means for controlling the delivery of doughnuts to the turnover device.

A still further object of the invention resides in providing means for controlling the rate of delivery of the doughnuts to the discharge device.

An object of the invention resides in providing means for completely obstructing the travel of doughnuts along the way to allow accumulation of the doughnuts within the way.

A still further object of the invention resides in providing a mechanism for procuring timed relative operation of the two means for controlling the rate of travel of the doughnuts along the way.

A feature of the invention resides in utilizing gates arranged for movement from positions obstructing the travel of doughnuts to positions free of the doughnuts.

Another object of the invention resides in using pairs of gates, said gates being spaced apart a distance to receive the doughnuts therebetween and being operated to procure alternate obstruction to the travel of the doughnuts along the way.

An object of the invention resides in pivoting the gates for swinging movement in substantially vertical planes.

Another object of the invention resides in utilizing cams for swinging said gates.

An object of the invention resides in providing a single operating member for operating all of said cams.

Other objects of the invention reside in the novel combination and arrangement of parts and in the details of construction hereinafter illustrated and/or described.

In the drawings:

Fig. 1 is a plan view of a doughnut machine illustrating an embodiment of my invention.

Fig. 2 is an end elevational view of the device shown in Fig. 1.

Fig. 3 is a plan sectional view taken on line 3—3 of Fig. 2.

Fig. 4 is an elevational sectional view taken on line 4—4 of Fig. 1 and drawn to a larger scale.

Fig. 5 is a view similar to Fig. 4 taken on line 5—5 of Fig. 1.

Fig. 6 is a fragmentary elevational view taken on line 6—6 of Fig. 1.

Fig. 7 is a sectional elevational view taken on line 7—7 of Fig. 1.

In doughnut machines where the travel of the doughnuts throughout the machine is procured by the flow of the cooking liquid and particularly where a turnover device operated by the flow of the cooking liquid is employed, the time required for the doughnuts to travel through the machine becomes irregular and lack of uniformity in the product results. The present invention overcomes this disadvantage by providing a construction in which the rate of travel both at the turnover device and at the discharge device are positively controlled.

My invention, as shown in Figs. 1 and 2, comprises a frame A constructed with legs 10 and lower cross frame members 11 connected thereto. The cross members 11 are disposed above the floor on which the frame rests and have attached to them a shelf 22 which serves a purpose to be presently described in detail. At the upper portion of the frame is provided a pan 12 to which the legs 10 are attached and which forms a part of the frame.

The pan 12 is constructed with a trough 13 forming a way along which the cooking liquid travels. The pan 12 is constructed in such a manner that the trough 13 is provided with a number of parallel runs 14, 15, 16 and 17. The runs 14 and 15 are connected together by an end run 18. The runs 16 and 17 are connected together by an end run 20 and the runs 14 and 17 being in turn connected together by an end run 21. By means of this construction a continuous way is formed, along which the cooking liquid is progressed and by means of which the doughnuts are caused to travel through the machine.

Above the run 21 of the trough 13 at the locality where the same is joined to run 14 is located a doughnut cutter and former 23. This doughnut cutter comprises a cylinder 24 supported on a support 25 mounted on the pan 12. The cylinder 24 communicates with a hopper 26 by means of which dough is fed into the cylinder. Within the cylinder 24 is disposed a piston 27 which draws the dough from the hopper 26 and discharges the same through a suitable nozzle 29 in a manner to deposit annular dough formations into the cooking liquid in the trough 55

13. A slide valve 28 controls the flow of dough into the cylinder and a similar valve mechanism 31 controls the discharge of dough from the cylinder and at the same time causes the dough to be discharged from the nozzle in annular form. This construction not constituting any particular feature of this invention, has not been disclosed in detail, though it can readily be comprehended that any type of doughnut cutter now well known in the art may be used for the purpose.

14. In the run 15 of the trough 13 is disposed a turnover device 32 which consists of a twisted channel by means of which the doughnuts are caused to become inverted when the same leave the end of the channel. A turnover device such as disclosed in the patent to Gunsolley No. 1,516,962 or any other similar type of turnover device may be used.

15. At the end of the run 17 of trough 13 is disposed an endless conveyor 33, which constitutes a discharge device for the doughnuts cooked in the machine. This conveyor consists of a frame 34 constructed of sheet metal, U-shaped in cross section, which is supported on a casting 35. The casting 35 is mounted on pan 12 and rotatably supports a shaft 36 to which a sprocket wheel 37 is attached. A similar sprocket wheel mounted for rotation at the end of the frame 34 supports a chain 38 which carries a number of flights 39. The conveyor 33 is arranged in inclined relation and dips into the cooking liquid in the run 17 of trough 13 so that the doughnuts delivered to it are carried by the conveyor upwardly and out of the machine and deposited upon a spout 41, discharging the same from the machine.

16. For the purpose of impelling the flow of cooking liquid through the way formed in the trough 13 a flow impelling device 42 is utilized. This device consists of a propeller wheel 43 which is emerged in the cooking liquid and which is attached to a vertically extending shaft 44. Upon rotation of this shaft the cooking liquid is raised from the run 17 and discharged into the run 14 which causes travel of the cooking liquid. This construction forming no particular feature of the invention, has not been shown in detail, though it can readily be comprehended that any suitable device may be used for the purpose.

17. The invention proper comprises four main gates 51, 52, 53 and 54 and additional gate 55. The two gates 51 and 52 form a set or pair which operate in coordination with one another to control the entry of doughnuts into the turnover device 32. The gates 53 and 54 similarly operate in coordination and control the delivery of doughnuts to the discharge device 33. The gate 55 is manually controlled and serves to block the operation of the gates 53 and 54, and thereby to procure accumulation of doughnuts along the way. These various gates will now be described in detail.

18. The gates 51 and 52 being substantially identical in construction, only the gate 52 will be described in detail. This gate is shown in Fig. 4 and consists of a wire loop 56 which extends transversely of the run 15 of trough 13. Issuing from the loop 56 is a vertical portion 57 which is connected to a horizontally extending arm 58. Arm 58 is attached to a block 59 which is mounted for oscillation upon a horizontally extending shaft 61. The gate 52 may be constructed of wire as illustrated in which case the arm 58 and the portion 57 are formed by using double reaches of wire and the ends of said reaches soldered into suitable holes drilled in the block 59. The shaft

61 is journaled in bearings 62, 63 and 64 which are secured to the uppermost portion of the pan 12. The blocks 59 of the two gates 51 and 52 are held in proper spaced position on the shaft 61 by means of spaced sleeves 65, 66 and 67 which extend up to the two bearings 62 and 63. It will thus be seen that the two gates 51 and 52 may swing about the shaft 61 as an axis from the two positions shown in Fig. 4. Inasmuch as the level of the cooking liquid within the trough 13 is approximately that indicated by the line 68, it will readily become apparent that when either of the gates is in its lowermost position that the doughnuts may travel on the surface of the cooking liquid free of the same and that when either of the gates is in its uppermost position the said doughnuts are engaged thereby and the travel of the doughnuts through the machine is obstructed.

19. For operating the gates the following construction is employed. A slide bar 71 is mounted for sliding movement in grooves 72 formed in the bearings 62, 63 and 64 and held in position within said grooves by means of keepers 73 bolted thereto. This slide bar has a cam 74 secured to it which is constructed with oppositely beveled cam surfaces 75 and 76 and an intermediate parallel portion 80. The blocks 59 to which the gates 51 and 52 are attached are constructed with depending arms 77. These arms have screws 78 and 79 screwed into the same, of which the screws 78 are adapted to engage the cam 74. In Fig. 4 screw 78 of gate 52 is shown in engagement with cam 74 having previously passed along the cam surface 76 to the parallel surface 80 of the cam. This elevates gate 52 so that the same is in a position to arrest the travel of the doughnuts to the conveyor 33. It will further be noted that the screw 78 of gate 51 clears the cam 74 so that this gate is in its lowermost position. When in such position, the said gate is below the position of the doughnuts in the cooking liquid and the doughnuts travel freely above the same. The two screws 79 serve as stops for limiting the downward movement of the cams and engage the slide bar 71 as shown in Fig. 4.

20. The gates 53 and 54 are shown in Figs. 1 and 5. These gates being identical in construction only the gate 54 will be described in detail. This gate consists of a length of wire which is bent 50 to form a loop 82 and a shank 83 extending upwardly therefrom. Shank 83 is twisted as indicated at 84 about a tube 85 and soldered to the same. The end of the shank 83 is bent to provide an arm 86 which terminates in a finger 87 55 extending outwardly from said arm and parallel to the tube 85. This finger is bent as shown in Fig. 7 to form a cam 88 having a raised portion 89 and a depressed portion 90. The tube 85 is rotatably mounted upon a shaft 92. Shaft 92 is 60 slidably and rotatably mounted in three bearings 94, 95 and 96 secured to the upper portion of the pan 12. The gate 53 is similarly constructed and attached to a tube 97. The tube 97 engages the end of the tube 85 and said tube engages bearing 96. A sleeve 98 mounted on the shaft 92 is disposed between the end of the tube 97 and the bearing 96, thereby restraining endwise movement of the parts. Encircling the two tubes 85 and 97 are two torsion springs 98 and 99. These 70 springs are anchored at one end to the respective gates and at their other ends to parts fixed relative to the pan 12. These springs are tensioned so that the same tend to force the gates 53 and 54 downwardly into the cooking liquid to the 75

position of the gate 82 shown in Fig. 5. Cooperating with the cams 88 of the two gates 53 and 54 are two rods 101 and 102 which are secured to clamps 103 attached to the slide bar 71. These rods are adapted to engage the portions 90 and 89 of said gates and to slide along the cam portion 88 thereof when moving from one position to the other. As these rods are reciprocated with the slide bar 71, the gates 53 and 54 are alternately raised and lowered.

It will be noted that the cam 74 is of a length such that when in one position the said cam engages both of the screws 78, thereby holding both of the gates in obstructing position. Likewise the two rods 101 and 102 are so positioned that in one position both of the gates 53 and 54 are held in obstructing position. By means of this construction both the gates of each pair are for a certain period of time held in obstructing position.

In order to cause the doughnuts to cook a predetermined length of time it becomes necessary to maintain the doughnuts in the way formed in trough 13 a predetermined length of time. This is accomplished in the normal operation of the machine by having the entire way up to the gates 51 and 52 filled with doughnuts. In the starting of the machine it hence becomes necessary to block the travel of doughnuts through the turnover device until the prescribed number of doughnuts have accumulated in advance of the same. This is accomplished in the following manner: Shaft 92 has attached to it a bracket 105 which is provided with a cam 106 extending along the same. This cam has a cam surface 107 which is adapted to engage under the arms 58 of gate 52. When the shaft 92 is slid inwardly as far as the same will go, cam 106 elevates the gate 52 and holds the same in such position. Subsequent operation of the machine permits the gate 51 to operate in the usual manner, which does not interfere with the blocking of the travel of doughnuts through the turnover device. When a prescribed number of doughnuts have been collected in advance of the turnover device, shaft 92 is drawn outwardly and the cam 106 disengaged from the arm 58 of said gate and the gate now functions in the normal manner to allow doughnuts one at a time to pass through the turnover device at the desired rate of speed.

In order to block the passage of doughnuts to the discharge device the gate 55 previously referred to is employed. This gate is constructed with a loop portion 108 adapted to extend into the cooking liquid at the locality of the doughnuts therein which has an arm 109 extending upwardly therefrom. Arm 109 is attached to a sleeve 111 rigidly secured to a shaft 112. Shaft 112 is journaled in the bearings 94 and 95 and is held from endwise movement therein by means of said sleeve and a collar 113. The end of said shaft is provided with a bent finger piece 114 by means of which the same may be rotated. It will thus become apparent that the gate 55 may be raised and lowered similar to the gates 53 and 54 to bring the same into the position arresting the travel of the doughnuts or to a position clear of the same. The bracket 105 supporting cam 106 is also engaged by shaft 112 and is thus held from rotation. This bracket slides freely along the shaft 112 when the shaft 92 is reciprocated.

For the purpose of operating the various mechanisms of the invention a transmission best shown in Figs. 1, 2 and 3 is employed. Mounted on the shelf 22 is an electric motor 116 which is con-

structed with an armature shaft 117. A belt 118 passes over a pulley 119 attached to said armature shaft and over another pulley 121 secured to a counter shaft 122. Counter shaft 122 is journaled in two bearings 123 and 124 secured to shelf 22. Counter shaft 122 has mounted on it a worm 125 which meshes with a worm wheel 126 mounted on a second counter shaft 127. This counter shaft is in turn journaled in two bearings 128 and 129 secured to the shelf 22. On the shaft 127 is a spur gear 131 which meshes with another spur gear 132 secured to a third counter shaft 133. This counter shaft is similarly journaled in bearings 134 and 135 secured to the shelf 22. On the shaft 133 is a disk 136 which has eccentrically attached to it a pin 137. Connected to this pin is a connecting rod 138 which extends upwardly from the disk and is connected at its upper end to a crank arm 139, being one of the arms of a bell crank indicated in its entirety by the reference numeral 140. The bell crank 140 includes a shaft 141 to which the arm 139 is attached together with another arm 142 also secured to said shaft and which extends generally upwardly therefrom. The shaft 141 is journaled in a bearing 143 secured to the leg 10 and pan 12. Arm 142 has pivotally connected to it a connecting rod 144 which in turn is pivotally connected to the end of the slide bar 71 by means of a pintle 145. It will thus be seen that as the shaft 133 rotates, slide bar 71 is reciprocated back and forth operating the various gates controlled thereby.

The shaft 122 has secured to the end of the same a pulley 146. A belt 147 passes over this pulley and over two idler pulleys 148 and 149 and finally over a pulley 151. The two idler pulleys 148 and 149 are freely mounted upon the shaft 36 and are disposed adjacent the bearing 35. The pulley 151 is mounted upon the shaft 44. The shaft 122 rotating at a relatively high rate of speed the propeller 43 is also driven at a corresponding rate of speed.

On the end of shaft 133 is a sprocket 152. A chain 153 passes over this sprocket and over another sprocket 154 secured to a counter shaft 155. Counter shaft 155 is journaled in two bearings 156 and 157 which are secured to a bracket 158 which in turn is secured to the pan 12 and the frame A. Shaft 155 has attached to it a clutch 159 which cooperates to drive a sleeve 161 revolute on said shaft. At the end of shaft 155 is a sprocket wheel 162. A chain 163 passes over this sprocket wheel and another sprocket wheel 164 fast on shaft 36. This chain is kept taut by means of an idler sprocket best shown in Fig. 2 and indicated by the reference numeral 165. By means of these sprockets and chain the conveyor 33 is operated and rotates continuously as long as the motor 116 is in operation.

The mechanism for operating the cutter 23 and associated parts includes two swinging levers 166 and 167. These levers are mounted for oscillation on a shaft 168 which is secured to bearings 169 and 170 mounted on the bracket 158. The lever 167 is pivoted to a piston rod 171 connected to piston 27 and has attached to it a pin 172 which in turn is connected to an eccentric 173 mounted on sleeve 161. As the sleeve rotates the piston 27 is reciprocated in opposite directions. Lever 166 is connected to the valve 28. This lever has mounted on it a roller 174 which engages a cam 175 on sleeve 161. As the said sleeve rotates the valve 28 is operated. Another lever 176 pivoted to a suitable support, not shown,

operates the valve 31. This lever has a roller 177 which engages a cam 178 fast on the sleeve 161. When the clutch 159 is engaged, the cutter and all of the mechanism associated with the same are set into operation. As soon as the clutch is disengaged these parts stop the gates and the conveyor continues to operate.

My invention operates as follows: Clutch 159 is first disengaged and the motor 116 started. This causes the gates 51, 52, 53 and 54 to move and the conveyor 33 to operate. At the same time the propeller 43 is set in motion which causes a circulation of the cooking liquid along the way within the trough 13. Before depositing doughnuts in the trough the cam 106 is forced inwardly to raise the gate 52 and hold the same in obstructing position. At the same time gate 55 is lowered to its obstructing position by rotating shaft 112. Clutch 159 is then moved into engaging position and the doughnut cutter commences to operate. As the doughnuts are formed, the same are deposited in the way and through the current of the cooking liquid are progressed until the first doughnut reaches the gate 51. Gate 51 operates continuously and if a doughnut should strike the said gate at the time the gate is in obstructing position the doughnut merely remains there until the gate moves to its clear position, whereupon it is progressed to the gate 52. This gate being held in obstructing position, the doughnut remains there. The operator then watches the machine until the run 14 and the run 18 of the trough are filled with the required number of doughnuts. Cam 106 is then disengaged and the two gates 51 and 52 operate normally. When the gate 51 is elevated the passage of doughnuts from the run 18 to the turner 32 is prevented. As this gate is moved into obstructing position gate 52 is lowered into a position free of the doughnuts and the doughnut trapped between these two gates is permitted to pass through the turnover device 32. The movement of the gates is thereafter reversed and the doughnut held by the gate 51 allowed to advance to a position between the two gates where the same is obstructed by the gate 52. As the gates function, doughnuts are directed one at a time to the turnover device and at a rate of speed consistent with the proper frying of the doughnuts. The doughnuts passing through the turnover device are obstructed by gate 55 and commence accumulating in runs 17, 19 and 16. When the required number of doughnuts are retained in said runs gate 55 is moved into its position clearing the doughnuts and the machine then operates normally. As the two gates 53 and 54 are operated, the same cause the delivery of doughnuts one at a time to conveyor 33 in a manner similar to gates 51 and 52. This conveyor elevates the doughnuts from the trough 13 and deposits the same upon the spout 41 from which the doughnuts are discharged to any suitable receptacle placed without the machine.

Although I have described the gates as being normally submerged below the positions of the doughnuts in the cooking liquid and being moved from such position upwardly and to obstructing position, yet it can readily be comprehended that the gates may be disposed above and/or out of the cooking liquid and alternately moved downwardly into obstructing position.

The advantages of my invention are manifest. An extremely simple and practical construction is provided whereby the uniform formation of doughnuts by a machine utilizing

liquid propulsion is procured. The device is extremely positive in action and simple in construction. The gates used with my invention do not injure the doughnuts.

Changes in the specific form of my invention, as herein disclosed, may be made within the scope of what is claimed without departing from the spirit of my invention.

Having described my invention, what I claim as new and desire to protect by Letters Patent is:

1. In a doughnut machine in which the doughnuts are progressed along a way through the flow of the cooking liquid, two gates extending across said way and spaced apart a distance to receive a doughnut therebetween, said gates being movable from positions obstructing the travel of the doughnuts along said way to positions free of the doughnuts, and means for moving said gates to procure alternate obstruction by the gates to the travel of the doughnuts along the way.

2. In a doughnut machine in which the doughnuts are progressed along a way through the flow of the cooking liquid, two gates extending across said way and spaced apart a distance to receive a doughnut therebetween, said gates being movable from positions obstructing the travel of the doughnuts along said way to positions free of the doughnuts, one of said gates being in one position while the other gate is in its other position, and means for reversing the positions of said gates.

3. In a doughnut machine in which the doughnuts are progressed along a way through the flow of the cooking liquid, two gates extending across said way and spaced apart a distance to receive a doughnut therebetween, said gates being movable from positions obstructing the travel of the doughnuts along said way to positions free of the doughnuts, one of said gates being in one position and the other gate being in the other position, and means for simultaneously reversing the positions of said gates.

4. In a doughnut machine in which the doughnuts are progressed along a way through the flow of the cooking liquid, two gates extending across said way and spaced apart a distance to receive a doughnut therebetween, means for guiding said gates for movement in substantially vertical planes from positions obstructing the travel of the doughnuts along said way to positions free of the doughnuts, and means for moving the gates to procure alternate obstruction by the gates to the travel of the doughnuts along the way.

5. In a doughnut machine in which the doughnuts are progressed along a way through the flow of the cooking liquid, two gates extending across said way and spaced apart a distance to receive a doughnut therebetween, means for pivoting said gates for swinging movement about substantially horizontal axes and substantially parallel with the direction of extent of the way at the locality thereof to cause the gates to move from positions obstructing the travel of the doughnuts along said way to positions free of the doughnuts.

6. In a doughnut machine in which the doughnuts are progressed along a way through the flow of the cooking liquid, two reticulate gates extending across said way and spaced apart a distance to receive a doughnut therebetween, said gates being movable from positions obstructing the travel of the doughnuts along said way to positions free of the doughnuts, and means for moving said gates to procure alternate obstruction by the gates to the travel of the doughnuts along the way.

7. In a doughnut machine in which the doughnuts are progressed along a way through the flow of the cooking liquid, two gates extending across said way and spaced apart a distance to receive a doughnut therebetween, said gates being movable from positions obstructing the travel of the doughnuts along said way to positions free of the doughnuts, and means for moving the gates to procure obstruction by one gate to the travel of the doughnuts while the other gate is free therefrom, thereafter to procure obstruction by both gates to the travel of the doughnuts along the way and subsequently thereto to procure obstruction by the second named gate to the travel of the doughnuts, while the first named gate is free therefrom.

8. In a doughnut machine in which the doughnuts are progressed along a way through the flow of the cooking liquid, two gates extending across said way and spaced apart a distance to receive a doughnut therebetween, said gates being movable from positions obstructing the travel of the doughnuts along said way to positions free of the doughnuts, and cams for moving said gates, said cams being timed to procure obstruction by one gate to the travel of the doughnuts while the other gate is free therefrom, thereafter to procure obstruction by both gates to the travel of the doughnuts along the way and subsequently thereto to procure obstruction by the second named gate to the travel of the doughnuts, while the first named gate is free therefrom.

9. In a doughnut machine in which the doughnuts are progressed along a way through the flow of the cooking liquid, two gates extending across said way and spaced apart a distance to receive a doughnut therebetween, means for pivoting said gates for swinging movement from positions obstructing the travel of the doughnuts along said way to positions free of the doughnuts, arms movable with said gates, and cams cooperating with said arms for swinging said gates to procure alternate obstruction by the gates to the travel of the doughnuts along the way.

10. In a doughnut machine in which the doughnuts are progressed along a way through the flow of the cooking liquid, two gates extending across said way and spaced apart a distance to receive a doughnut therebetween, said gates being movable from positions obstructing the travel of the doughnuts along said way to positions free of the doughnuts, means for moving said gates to procure alternate obstruction by the gates to the travel of the doughnuts along the way, and a third gate in advance of said first named gates movable from a position obstructing the travel of the doughnuts along said way to a position free of the doughnuts, and manually controlled means for selectively moving said third named gate to either of its two positions and for holding said gate in either of such positions.

11. In a doughnut machine in which the doughnuts are progressed along a way through the flow of cooking liquid and in which a turnover device and a discharge device are utilized and situated at spaced localities along said way, a pair of gates in advance of said discharge device extending across said way and spaced apart a distance to receive a doughnut therebetween, said gates being movable from positions obstructing the travel of the doughnuts along said way to positions free of the doughnuts, a second pair of gates in advance of said turnover device

ing across said way and spaced apart a distance to receive a doughnut therebetween, said second pair of gates being movable from positions obstructing the travel of the doughnuts along said way to positions free of the doughnuts, means for moving the gates of the first pair to procure control of the travel of the doughnuts along said way, and means for moving said gates of the second pair to procure like control of the travel of the doughnuts.

12. In a doughnut machine in which the doughnuts are progressed along a way through the flow of cooking liquid and in which a turnover device and a discharge device are utilized and situated at spaced localities along said way, a pair of gates in advance of said discharge device extending across said way and spaced apart a distance to receive a doughnut therebetween, said gates being movable from positions obstructing the travel of the doughnuts along said way to positions free of the doughnuts, a second pair of gates in advance of said turnover device extending across said way and spaced apart a distance to receive a doughnut therebetween, said second pair of gates being movable from positions obstructing the travel of the doughnuts along said way to positions free of the doughnuts, means for moving the gates of the first pair to procure control of the travel of the doughnuts along said way, means for moving said gates of the second pair to procure like control of the travel of the doughnuts, and means for procuring correspondingly timed movement of both pairs of gates.

13. In a doughnut machine in which the doughnuts are progressed along a way through the flow of cooking liquid and in which a turnover device and a discharge device are utilized and situated at spaced localities along said way, a pair of gates in advance of said discharge device extending across said way and spaced apart a distance to receive a doughnut therebetween, said gates being movable from positions obstructing the travel of the doughnuts along said way to positions free of the doughnuts, a second pair of gates in advance of said turnover device extending across said way and spaced apart a distance to receive a doughnut therebetween, said second pair of gates being movable from positions obstructing the travel of the doughnuts along said way to positions free of the doughnuts, cams for moving all of said gates in predetermined correspondence and relation, and a single operating member for operating all of said cams.

14. In a doughnut machine in which the doughnuts are progressed along a way through the flow of cooking liquid and in which a turnover device and a discharge device are utilized and situated at spaced localities along said way, a pair of gates in advance of said discharge device extending across said way and spaced apart a distance to receive a doughnut therebetween, said gates being movable from positions obstructing the travel of the doughnuts along said way to positions free of the doughnuts, a second pair of gates in advance of said turnover device extending across said way and spaced apart a distance to receive a doughnut therebetween, said second pair of gates being movable from positions obstructing the travel of the doughnuts along said way to positions free of the doughnuts, means for moving the gates of the first pair to procure control of the travel of the doughnuts along said way, means for moving

said gates of the second pair to procure like control of the travel of the doughnuts, another gate positioned in advance of one pair of gates, said gate being movable from a position obstructing the travel of the doughnuts along said way to a position free of the doughnuts, and manually operated means for moving said gate from one position to the other.

15. In a doughnut machine in which the doughnuts are progressed along a way through the flow of cooking liquid and in which a turnover device and a discharge device are utilized and situated at spaced localities along said way, a pair of gates in advance of said discharge device extending across said way and spaced apart a distance to receive a doughnut therebetween, said gates being movable from positions obstructing the travel of the doughnuts along said way to positions free of the doughnuts, a second pair of gates in advance of said turnover device extending across said way and spaced apart a distance to receive a doughnut therebetween, said second pair of gates being movable from positions obstructing the travel of the doughnuts along said way to positions free of the doughnuts, means for moving the gates of the first pair to procure control of the travel of the doughnuts along said way, means for moving said gates of the second pair to procure like control of the travel of the doughnuts, another gate positioned in advance of one pair of gates, said gates being movable from a position obstructing the travel of the doughnuts along said way to a position free of the doughnuts, manually operated means for moving said gate from one position to the other, and means for rendering one of the gates of the other pair inoperative.

16. In a doughnut machine in which the doughnuts are progressed along a way through the flow of cooking liquid and in which a turnover device and a discharge device are utilized and situated at spaced localities along said way, a pair of gates in advance of said discharge device extending across said way and spaced apart a distance to receive a doughnut therebetween, said gates being movable from positions obstructing the travel of the doughnuts along said way to positions free of the doughnuts, a second pair of gates in advance of said turnover device extending across said way and spaced apart a distance to receive a doughnut therebetween, said second pair of gates being movable from positions obstructing the travel of the doughnuts along said way to positions free of the doughnuts, means for

moving the gates of the first pair to procure control of the travel of the doughnuts along said way, means for moving said gates of the second pair to procure like control of the travel of the doughnuts, and means for rendering one of the gates of one of the pair of gates inoperative.

17. In a food cooking machine having a circuitous channel and means for continuously circulating therein a cooking liquid wherein the food is floated, a pair of gates for stopping the food from moving with the liquid and releasing the same to move with the liquid, the gates being spaced longitudinally of the channel to admit a predetermined number of food portions between them and mounted for movement alternately of each other to a position in the path of the food in the channel for engaging the same and for reverse movement releasing the same.

18. In a doughnut machine in which the doughnuts are progressed along a way through the flow of the cooking liquid, two gates disposed in the way and spaced apart in the direction of travel of the doughnuts, said gates being movable from positions obstructing the travel of the doughnuts along said way to positions free of the doughnuts, and means for moving said gates to procure alternate obstruction by the gates to the travel of the doughnuts along the way.

19. In a doughnut machine in which the doughnuts are progressed along a way through the flow of the cooking liquid, a gate disposed in the way, means for guiding said gate for movement from a position obstructing the travel of doughnuts along the way to a position clear of the doughnuts, and time controlled means for holding said gate stationary in obstructing position for a predetermined period and for subsequently moving said gate out of its obstructing position and back into obstructing position.

20. In a doughnut machine in which the doughnuts are progressed along a way through the flow of the cooking liquid, a gate disposed in the way, means for guiding said gate for movement from a position obstructing the travel of doughnuts along the way to a position clear of the doughnuts, and operating means including a cam for operating said gate, said cam having a surface maintaining said gate stationary in obstructing position for a predetermined period and having another surface for subsequently moving said gate out of obstructing position, said operating means moving said gate back into obstructing position.

PETER J. TOEWS.
